FRAME FOR ASSISTING IN DESIGNING AND
MEASURING LAMP SHADES

Virginia M. Harlow, New York, N. Y.

Application January 14, 1950, Serial No. 138,624

4 Claims. (Cl. 33—175)

1

The invention herein disclosed is a device for measuring, planning and designing lamp shades.

Objects of the invention are to provide a practical form of frame construction capable of being extended and contracted in various ways to outline different sizes and shapes of lamp shades.

Particularly it is a purpose of the invention to provide apparatus of this character, of simple, inexpensive and easily adjusted construction and which will be capable of use for designing and planning lamp shades of many different styles and forms.

Further special objects of the invention are to provide the apparatus in the form of a frame in the general resemblance of a lamp shade frame and made up of adjustably related components which in themselves will be adjustable independently of other components.

Other desirable objects attained by the invention are set forth or will appear in the course of the following specification.

The drawings accompanying and forming part of the specification illustrate certain present practical embodiments of the invention. Structure, however, may be modified and changed as regards the immediate illustration, all within the true intent and broad scope of the invention as hereinafter defined and claimed.

Fig. 1 in the drawings is a plan view of one of the adjustable lamp shade frameworks with parts broken and appearing in section;

Fig. 2 is a broken vertical sectional view taken on substantially the plane of line 2—2 of Fig. 1 and showing particularly one of the extensible struts or stays connecting the upper and lower rings of the frame;

Fig. 3 is a side elevation of the frame;

Fig. 4 is a broken part sectional detail showing the adjustable center support;

Fig. 5 is a broken and part sectional plan view showing the frame partly extended;

Fig. 6 is a broken and vertical sectional view showing the frame with ring connecting struts extensible at both ends;

Fig. 7 is a broken side elevation showing a form of construction for mounting the frame on a bowl or canopy form of shade construction.

As shown particularly in Figs. 1, 2 and 3, the framework is made up of upper and lower adjustable ring or hoop members 9 and 10 connected at intervals by extensible stays or struts

2

11, and radially extensible arms 12 connected with the top ring and carrying a center support 13.

These several elements are made up for the most part of telescopically engaged, oversliding tubes and wire parts.

Thus the rings are shown as composed of segmental tubular sections 14 in which are slidably held segmental wire sections 15 and the upright struts 11 are shown as made up of straight tubular members 16 having wires 17 slidably engaged therein.

The upright tubes 16 are shown as having angularly disposed sleeves 18 at the upper ends of the same rotatably engaged over the wire segments 15 of the upper ring, and the wires 17 are shown as having similar sleeves 19 at the lower ends rotatably engaged over the wire segments 15 of the lower rings.

In the illustration the stays are swiveled at 18 over the segmental wires 15 at points between the ends of the tube segments 14. This keeps the size of the swivel sleeves 18 down to small diameter but it is contemplated that these sleeves may be swiveled over the tubular sections 14, or some of the stays may be swiveled over the wires and others over the tubular sections, the arrangement selected being determined to some extent by the number of stays employed, and consequently the number of segments of the wires and tubes.

The radial arms 12 forming the spider structure for the upper ring or hoop are shown as extensible and contractible by having straight tube sections 20 secured in radial relation to the tube segments 14 and wire or rod sections 21 sliding in these tube sections and secured to the central supporting ring or collar 13.

The construction described provides practically a universally adjustable frame. The upper and lower rings can be adjusted to larger and smaller diameters independently of each other and these independently adjustable rings can be approached or separated from each other by collapsing or extending the telescopically adjustable side struts 11.

The telescopically constructed spider arms permit free adjustment of the upper ring while maintaining the center support 13 at the center of the frame in all adjustments of the parts.

To provide some measure and indication of

the adjustments, the telescopically related parts may have graduations or size markings thereon.

The inner sliding rod elements are shown as having notches 22 which may be spaced at quarter inch, half inch, or other selected distances convenient for measuring or indicating purposes. These notches may indicate size by the number of them exposed at the ends of the tubular members, or size markings may be applied to the wires or other parts where they can be readily seen for different size adjustments.

While the oversliding parts may normally hold by reason of their frictional engagement, it may be desirable to have them yieldingly retained in their positions of adjustment. The latter effect is attained in the present disclosure by indenting the tubular members as indicated at 23, to yieldingly grip the notches 22 in the enclosed sliding wire members.

To provide height adjustment the central supporting collar 13 may be internally screw threaded as indicated at 24, to receive a correspondingly screw threaded, tubular height determining sleeve or sleeve sections such as shown at 25, Fig. 4. While different length supporting tubes 25 may be provided, it is considered that all necessary height adjustments may best be effected by providing a number of relatively short tube sections, any selected number of which may be screwed together to raise the framework to the desired level, supported by said tube section on a lamp globe or other support.

Fig. 6 shows how greater extension of the side struts may be effected by interposing between the companion tube and wire elements 16, 17, a coupling or extension sleeve 26 sliding over the tube 16 at one end and reduced at the opposite end at 27 to slide over the wire 17.

The frame may be used for all kinds and sizes of lamp shades and for all the various ways in which lamp shades are usually supported. The top, spider form of support shown, and particularly with the height adjustment feature, may be suitable for most purposes.

Fig. 7 shows how the framework may be mounted on a bowl or canopy type of lamp by providing an adjustable cross bar 28 adapted to rest on the rim of a canopy such as indicated at 29. This cross bar is shown as made up of telescopically engaged tube and rod members 30, 31, pivotally connected at their ends at 32, 33, with sleeves 34, 35, vertically slidable over the side struts 11 and secured in vertically adjusted relation as by wing nuts or set screws 36. By adjusting this bar up or down and securing it in different positions on the struts, the frame may be supported at different levels on a lamp fixture of the canopy type to produce different lamp shade effects.

Adjustment of the frame to different sizes and shapes is easily effected by simply pulling and pushing on the telescopically related elements of the various units, and the markings on these units provide a desired index of size while such adjustments are being effected. The construction is relatively simple and inexpensive and the various parts can be made up of standard tubing and wire or rod.

The frame, constructed as disclosed, with slip joint and swivel connections provides a flexible form of smooth contour, free of projections and adapted to serve as a support for shaping the various kinds of shade materials usually employed, such as silk, satin, plastic, parchment, paper and the like. By its substantially universal

adjustability the invention provides a frame which can be molded to different sizes and shapes for draping different lamp shade materials thereover to obtain desired lamp shade effects.

5 While a circular type of framework has been disclosed, the invention contemplates various kinds of shapes such as oval, square and various angular formations. The number, size and shape of the segments forming the rings or hoops, and the number, length and extensibility of the stays or struts accordingly may be varied to suit these different requirements.

10 The oversliding tube and wire elements constituting the frame may be of flexible or springy material to further provide for and facilitate the various adjustments described. While these elements ordinarily may be of metal, it is contemplated that they may be of other materials such as plastic and the like.

15 What is claimed is:

1. A frame for aiding the design of lamp shades, substantially universally adjustable as to size and shape and comprising top and bottom rings composed of telescopically engaged segmental wires and tubes and longitudinally extensible and contractible struts connecting said rings in variously spaced relation and composed of telescopically engaged, straight rod and tube sections having transverse sleeves at the ends of 20 the same swiveled on the segmental rods of the rings between the segmental tubes of said rings and thereby spaced circumferentially of said rings.

2. A frame for aiding the design of lamp shades, substantially universally adjustable as to size and shape and comprising top and bottom rings composed of telescopically engaged segmental wires and tubes and longitudinally extensible and contractible struts connecting said rings in variously spaced relation and composed of telescopically engaged, straight rod and tube sections having transverse sleeves at the ends of 25 the same swiveled on the segmental rods of the rings between the segmental tubes of said rings and thereby spaced circumferentially of said rings, and a spider connected with the top ring and composed of longitudinally adjustable, telescopically connected, straight rods and tubes secured in radial relation to the segmental tubes of 30 said top ring.

3. A frame for aiding the design of lamp shades, substantially universally adjustable as to size and shape and comprising top and bottom rings composed of telescopically engaged segmental wires and tubes and longitudinally extensible and contractible struts connecting said rings in variously spaced relation and composed of telescopically engaged, straight rod and tube 35 sections having transverse sleeves at the ends of the same swiveled on the segmental rods of the rings between the segmental tubes of said rings and thereby spaced circumferentially of said rings, a spider connected with the top ring and composed of longitudinally adjustable, telescopically connected, straight rods and tubes secured in radial relation to the segmental tubes of said top ring, and a central supporting post of vertically adjustable extent removably connected with 40 said spider.

4. A frame for aiding the design of lamp shades, substantially universally adjustable as to size and shape and comprising top and bottom rings composed of telescopically engaged segmental wires and tubes and longitudinally exten- 45

sible and contractible struts connecting said rings in variously spaced relation and composed of telescopically engaged, straight rod and tube sections having transverse sleeves at the ends of the same swiveled on the segmental rods of the rings between the segmental tubes of said rings and thereby spaced circumferentially of said rings, and a cross bar of telescopically engaged, straight rod and tube sections having sleeves at the ends of the same slidably engaged over oppositely disposed struts.
